[57] **CLAIM**

The ornamental design for a decanter, substantially as shown and described.

DESCRIPTION

FIG. 1 is a front elevational view of a decanter showing my new design, it being understood that the ribbing on the sides of the bottle, partly shown in full lines, are continuous around the entire periphery of the bottle as shown by the dash-dot lines and are interrupted only by the bottle neck and base;

FIG. 2 is a rear elevational view thereof;

FIG. 3 is a side elevational view;

FIG. 4 is a top plan view;

FIG. 5 is a bottom plan view; and

FIG. 6 is a fragmentary sectional view taken on line 6—6 of FIG. 1.
